Primary Examiner — T. Chase Nelson*Assistant Examiner* — Mark Cavanna(74) *Attorney, Agent, or Firm* — Barnes & Thornburg LLP(57) **CLAIM**The ornamental design for a head rail for a patient bed, as
shown and described.

DESCRIPTION

FIG. 1 is a top front perspective view of a head rail for a
patient bed showing our new design;FIG. 2 is a top rear perspective view of the head rail of FIG. 1;
FIG. 3 is a bottom front perspective view of the head rail of
FIG. 1;FIG. 4 is a bottom rear perspective view of the head rail of
FIG. 1;FIG. 5 is a front elevation view of the head rail of FIG. 1;
FIG. 6 is a rear elevation view of the head rail of FIG. 1;FIG. 7 is an end elevation view of a first end of the head rail of
FIG. 1;FIG. 8 is an end elevation view of a second end of the head rail
of FIG. 1;FIG. 9 is a top plan view of the head rail of FIG. 1; and,
FIG. 10 is a bottom plan view of the head rail of FIG. 1.**1 Claim, 6 Drawing Sheets**(56)
